UNITED STATES PATENT OFFICE.

CESARE BARBIERI, OF NEW YORK, N. Y., ASSIGNOR TO THE VORTEX MFG. CO., OF CHICAGO, ILLINOIS, A CORPORATION OF ILLINOIS.

SUNDAE-DISH-FORMING MACHINE.

Application filed November 6, 1924. Serial No. 748,009.

This invention relates to improvements in sundae dish forming machines and more particularly to a machine unit which may be independently connected up to receive a drive 5 from a main driving shaft for the purpose of permitting a series of sundae dish forming machine units to be connected with the main driving mechanisms in such a way that the units may be independently controlled 10 without interfering with the operation of the remaining units.

It is an object of this invention to provide an improved sundae dish forming machine provided with means whereby the various 15 mechanisms comprising the machine may be disconnected from the driving means without necessitating the stopping of other machine units connected with said driving means.

It is also an object of this invention to provide an improved sundae dish forming machine which may be independently connected to receive a drive from a driving mechanism and further adapted to manufacture conical 20 sundae dishes from blanks which are adapted 25 to be automatically delivered from a blank holding magazine and transferred into the field of operation of forming mechanisms which act to automatically form the blanks into sundae dishes which are then delivered 30 into a position to be automatically stacked in nested relation one within the other below suitable retaining means with the folded portions of adjacent dishes staggered to permit the dishes to be stacked in a straight column 35 within a stacking tube.

It is a further object of this invention to provide a sundae dish forming machine unit wherein a dish blank feed mechanism is adapted to automatically deliver blanks into 40 a position wherein a lifting pin mechanism is adapted to raise a portion of the advanced blank in order that the blank may be more readily operated upon by forming mechanisms which act to form the blank into a 45 sundae dish which when formed is automatically removed from the forming means and delivered into a rotatable sundae dish support which forms a part of a stacking mechanism.

50 It is furthermore an object of the invention to provide an improved sundae dish forming machine wherein clutch controlled cam mechanisms are provided for governing the operation of dish delivering and stacking mechanisms, the operation of which is controlled

by means of a starting or stopping device connected with the clutch and adapted to govern said cam mechanisms.

It is an important object of this invention to provide an improved sundae dish forming 60 machine wherein the feeding, forming, discharging and stacking mechanisms are adapted to be governed by a starting or control device which in turn governs a clutch mechanism provided for the purpose of permitting the machine unit to be connected with or disconnected from a main driving shaft 65 without interfering with the operation of similar machines which may be connected to receive a drive from the same driving 70 shaft.

It is also an important object of this invention to provide a dish forming unit having the mechanisms so arranged that the unit may be easily connected with or disconnected 75 from a main driving shaft without necessitating the shutting down of similar machines which may also be connected with said driving shaft.

Other and further important objects of 80 this invention will be apparent from the disclosures in the specification and the accompanying drawings.

This invention (in a preferred form) is illustrated in the drawings and hereinafter 85 more fully described.

On the drawings:

Figure 1 is a front elevation of a complete improved sundae dish forming machine unit embodying the principles of this invention and having mechanisms permitting the unit to be independently connected with or disconnected from driving shafts with which other units may be independently connected.

Figure 2 is a top plan view of the sundae dish forming machine unit.

Figure 3 is a vertical sectional view taken on line 3-3 of Figure 1.

Figure 4 is an enlarged fragmentary sectional view with parts shown in elevation taken on the line 4-4 of Figure 3.

Figure 5 is a fragmentary sectional view taken on line 5-5 of Figure 1.

Figure 6 is a fragmentary transverse sectional view taken on line 6-6 of Figure 2.

Figure 7 is an enlarged fragmentary vertical section of the dish blank feed mechanism taken on line 7-7 of Figure 2.

Figure 8 is a detail section of the dish 110

blank feed mechanism taken on line 8—8 of Figure 7 showing parts in elevation.

Figure 9 is an enlarged detail plan view taken on line 9—9 of Figure 3 with parts broken away to show the construction of the upper portion of the dish stacking mechanism.

Figure 10 is a fragmentary detail section taken on line 10—10 of Figure 9.

10 Figure 11 is a fragmentary detail view taken on line 11—11 of Figure 3.

Figure 12 is a fragmentary sectional view taken on line 12—12 of Figure 3 with parts omitted.

15 Figure 13 is a fragmentary sectional view taken on line 13—13 of Figure 3.

Figure 14 is a plan view treated diagrammatically covering a plurality of machine units connected to a common driving mechanism.

20 Figure 15 is a fragmentary detail section of the dish forming mechanisms taken on line 15—15 of Figure 2, with parts shown in elevation and with parts omitted.

25 As shown on the drawings:

The improved machine is of the multiple type made up of a plurality of units each adapted to be independently connected with a common driving source so that one or more 30 of the units may be independently disconnected from the driving source without necessitating the stopping of all of the units comprising the entire machine line-up. Only 35 one of the units is illustrated and will be described coacting with the common driving source.

The reference numeral 1 indicates a main machine frame having supported thereon in suitable bearings a main cam shaft 2 on one 40 end of which a driving pulley 3 is secured. The pulley 3 is adapted to be driven by means of a belt connected with any suitable source of driving power. Secured on the cam shaft 2 within the machine frame 1 is a gear 4 45 which is in mesh with a gear 5. The gear 5 is secured on a stub shaft 6 which is journaled in bearings at one end of the machine frame. Secured on the outer end of the shaft 6 is a disk 7 having a roller 8 mounted on the 50 periphery thereof for coaction with a four-point Geneva gear 9. The Geneva gear 9 is fixed on the outer end of a shaft 10 supported on the machine frame and having a gear 11 keyed or otherwise secured thereon. The 55 gear 11 meshes with a pinion 12 fixed on one end of a longitudinal driving shaft 13 supported in suitable bearings 14 on the machine frame. Fixed on the shaft 13 is a bevel gear 14 which drives a bevel gear 15 provided for the purpose of operating the folding or forming mechanisms of the machine.

60 Mounted on the cam shaft 2 is a sprocket wheel 16 around which an endless chain 17 is trained. The chain 17 is also trained 65 around a smaller sprocket wheel which is

mounted on a shaft 18 supported in suitable bearings 19 (Figure 2). A drive from the shaft 2 is thus adapted to be transmitted through the chain 17 to the auxiliary shaft 18 from which the blank feed mechanisms 70 are adapted to be driven.

Secured on the auxiliary shaft 18 is a bevel pinion 20 which is in mesh with a bevel gear 21. The bevel gear 21 is securely mounted on one end of a hollow shaft 22 (Figure 8) 75 which is journaled in a housing or box section 23 supported on the machine frame. Slidably projecting into the hollow shaft 22 is a slidable rod or stem 24 having a knob or handle 25 fixed on the outer end thereof. Secured diametrically through the rod 24 is a drive pin 26 the ends of which project through slots 27 provided in the hollow shaft 22 (Figure 8). The slots 27 limit the telescoping movement of the rod 24 in the hollow shaft 22 whereby the blank feed mechanism may be manually released when desired. The ends of the pin 26 are adapted to coact with a pin 28 to cause rotation of a blank feed reel on which said pin 28 is mounted. The blank feed reel is rotatably supported on the hollow shaft 22 within the box 23 and comprises a pair of spaced circular plates or disks 29 integrally connected by bars 30. Supported on one of the reel bars 30 between the disks 29 is a curved blank feed friction pad 31 made of rubber or other suitable material. The friction pad 31 extends around a portion of the feed reel so as to operate a dish blank to be fed forwardly into the machine only at a predetermined time.

90 Mounted on the machine frame is a table 32 having an opening therein above the box 23 through which the feed reel is adapted to act upon dish blanks which are supported in a circular magazine 33 mounted on the table 32 above said opening. Supported in the box 23 is a bracket 34 holding a pin 35 which projects upwardly through the opening in the table 32 to afford a support for the stack of dish blanks within the magazine (Figure 7). A pair of blank feed rollers 36 and 37 are provided to engage blanks which are fed therebetween by the feed reel friction pad 31. The upper feed roller 36 is supported in pivoted bearing arms 38 which are held in lowered position by means of coil springs 39. Fixed on one end of the upper roller shaft 40 is a pinion or small gear 41 which is in mesh with a gear 42 supported on one end of the lower roller shaft 43 which is journaled in suitable bearings in the box 23. Fixed on the other end of the lower roller shaft 43 is a gear which is in mesh with a gear 44 supported on a stub shaft mounted on the box 23. Also fixed on said stub shaft adjacent the gear 44 is a small gear 45 which is in mesh with a large gear 46 on the hollow shaft 22 adjacent the bevel gear 21.

95 100 105 110 115 120 125 130

Fixed on the hollow shaft 22 adjacent one

end of the feed reel is a cam 47 (Figure 7) adapted to coact with a roller 48 supported on one side of a slotted or bifurcated bar 49 having the slot positioned to permit the 5 forked end of the bar to slide transversely on the hollow shaft 22. The other end of the bar 49 is pivoted to one end of a crank 50 fixed on a rocker shaft 51 supported by brackets 52 secured to or formed on the box 10 23. Secured on the rocker shaft 51 is a pair of pusher arms 53 which operate together to engage a dish blank after it passes between the feed rollers 36 and 37. The upper ends or tips of the pusher arms 53 operate in 15 spaced parallel slots 54 provided in the machine table 32. The lower feed roller 37 is provided with spaced peripheral grooves adapted to receive the pusher arms 53 when in retracted position. Positioned on the top 20 of the table 32 are a pair of spaced rollers or stops 55 against which a dish blank is adapted to engage when pushed over the table 32 by the pusher arms 53.

Projecting upwardly into an aperture in 25 the table 32 is the upper end of a pin or rod 56 adapted to be projected through the table aperture at predetermined times for the purpose of elevating the advanced portion of a dish blank after it has been fed forwardly 30 on the table 32 by the blank feeding mechanisms.

The lower end of the pin 56 is pivotally supported on one end of a bar 57 which is fulcrumed intermediate its ends on a shaft or stud 58 supported on a bracket arm 59 (Figure 6). A roller 60 is supported on the other end of the fulcrum bar 57 to coact with a cam 61 mounted on the cam shaft 2.

The shaft 13 is intermittently rotated by 40 the action of the four point Geneva gear 9 and the dish forming mechanism is driven thereby through the bevel gears 14 and 15. The forming mechanism is mounted on a shaft journaled in bearings 62 supported on 45 the machine frame. The bevel gear 15 is fixed on the outer end of said shaft for the purpose of causing rotation of said shaft when the machine is in operation. Also supported on the forming mechanism shaft is 50 a clutch mechanism 63 and a hand wheel 64 for operating the same to permit the dish forming elements to be brought into proper timed relation with the blank feeding means. Mounted pivotally on the inner end of the 55 dish forming shaft are two gripper holder members 190 adapted to cooperate with each other and each having attached to its forward end a forward extending gripper plate 191 which preferably is in the form of a flat triangular plate. The dish forming mechanism is constructed similar to the arrangement disclosed in my patent for a sundae cup forming machine, Patent No. 1,535,757, dated April 30, 1925. The gripper holder 60 members 190 and the gripper plates 191 are

normally held in close contacting position by spring means connecting said holder members and are adapted to be separated at predetermined times in order to permit a blank to be inserted therebetween. A forming 70 member 65 (Figure 2) of a semi-conical shape is associated with the gripper plates 191 and is provided with two rearwardly extending arms 66 pivoted to the opposite sides of the innermost bearing 62. A cross bar 67 connects the two pivoted arms 66 and said bar has supported thereon a Z bracket 68, the lower end of which engages the upper gripper holding member 190 in such a manner that when the forming member 65 is elevated about its pivot 69 the gripper plates 191 are separated against the tension of their controlling spring. Projecting through an opening in the upper flange of the Z bracket 68 is a stem the lower end of which is connected with the cross bar 67. The stem has the upper end thereof secured in an arm 70 adjustably supported on a vertical rod 71 by means of a set screw 72. The rod 71 is rigidly supported on the front bearing member 90 62. A coiled spring 73 is engaged around said stem below the arm 70. The spring 73 serves to resiliently hold the forming member 65 in its lower position.

An additional blank positioning mechanism is provided and comprises a pair of arms 74 adapted to slide in slots 75 in the table 32. The upper ends of the arms 74 have positioning pins secured thereon. The lower ends of the arms 74 are supported on 100 a crank arm 76, the lower end of which is fixed on one end of a stub shaft 77 journaled in a bearing 78 (Figure 13). Secured on the other end of the shaft 77 is a bell crank 79 having a set screw 80 adjustably mounted in the upper end of the longer arm of said bell crank to coact with a stop block 81 (Figure 3) fixed on the machine frame. A spring 82 is connected to the longer arm of the bell crank 79 and to the stop block 81 to resiliently 105 hold the blank positioning arms 74 in retracted normal position and the set screw 80 in engagement with the stop block 81 as shown in Figure 3. A roller 83 is mounted on the end of the short arm of the bell crank 79 to coact with a cam 84 mounted on the cam shaft 2.

The means for lifting the forming member 65 consists of an arm 85 pivoted at 86 to the machine frame and having a roller 87 supported on the free end thereof. The roller 87 is positioned to coact with a cam 88 supported on the cam shaft 2 and separated from the cam 84 by a spacer disk. Pivotally supported on the free end of the arm 85 is the lower end of an upwardly directed bar or arm 89. The upper end of the arm 89 is positioned to coact with a fulcrumed arm 90 which is contacted by a slidable shoe 91 engaged on one of the pivoted arms 66 to 125 130

permit the forming member 65 to be elevated with the cam 88 coaxing with the roller 87 positioned to swing the arm 85 upward. Forming a part of the arm 90 is a presser arm 92 adapted to cooperate with a V shaped opening or slot 93 provided in the table 32. The triangular slot 93 is provided for the purpose of accommodating the triangular gripping plates which form a part of the 10 dish forming mechanism.

A mechanism is provided for automatically delivering or transferring a formed dish from the forming mechanism to a stacking mechanism. The dish transfer mechanism 15 comprises a horizontal stationary guide bar 94 supported on the machine frame below a transverse guide slot 95 in the table 32. Slidably mounted on the guide bar 94 is a block or shoe 96 on one side of which a pin 97 is secured (Figure 3). Fastened to the opposite side of the slidable shoe 96 is a plate 98 which projects upwardly through the table slot 95. Supported on the upper projecting portion of the plate 98 is one end of a dish transfer bracket 99 adapted to engage a formed dish to push the same toward discharge position.

Engaging the pin 97 of the dish transfer mechanism is the upper notched or U shaped 30 end 100 (Figure 3) of a long bell crank arm 101 the lower end of which is integrally formed on a sleeve or collar 102 which is rotatably supported on a longitudinally directed shaft 103. The shaft 103 is supported 35 in suitable bearings on the machine frame. Also integrally connected with the bell crank sleeve 102 is a shorter curved bell crank arm 104. Pivots connected to the free end of the curved bell crank arm 104 is the upper 40 end of a connecting rod 105 the lower end of which is pivotally connected to the end of the long arm 106 of a bell crank member which also has a short arm 107. The bell crank 106-107 is pivotally engaged on a 45 shaft 108 supported by a bracket 109 and by a bracket 110. The bracket 109 is secured to the machine frame while the bearing bracket 110 is supported upon a bearing bracket 111 securely mounted on a cross member of the machine frame 1. Rotatably 50 mounted on the end of the short bell crank arm 107 is a roller 112 which is positioned to track on the periphery of a cam 113, which forms a part of a clutch sleeve 117 which is 55 loosely engaged on the shaft 114. The shaft 114 is supported by the bearing bracket 111 and by a bearing bracket 115 which is also secured to the machine frame. Securely 60 mounted near one end of the shaft 114 is a sprocket wheel around which an endless chain 116 is trained. The chain 116 is also trained around a sprocket wheel which is mounted on the main driving or cam shaft 2 to the inside of the gear 4.

65 Also mounted on the clutch sleeve 117 is

a bevel gear 118. As illustrated in Figure 4 the loose clutch sleeve 117 has integrally formed thereon a cam 119 positioned adjacent the cam 113. A clutch pin 120 projects from one side of the cam 113 and is positioned 70 to project into an opening or notch 121 provided in one end of a shiftable clutch collar 122 engaged on the shaft 114 to receive a drive therefrom through a pin 123 which projects radially from said shaft. The pin 120 75 on the cam 113 coaxing with the notch in the shiftable clutch collar 122 forms a one point clutch unit.

The clutch collar 122 is adapted to be shifted or operated by a yoke arm 124 having pins 125 supported in the ends thereof and adapted to project into a peripheral groove 126 provided in the shiftable clutch collar 122. The clutch operating yoke 124 is secured to the lower end of a vertical shaft 127. The shaft 127 is journaled in the bracket 109 and in a bracket 128 supported on the machine frame. Secured on the upper projecting end of the vertical shaft 127 is a bracket arm 129 having openings in the outer end thereof. Connected to the outer end of the bracket arm 129 is one end of a coil spring 130 the other end of which is secured to the machine frame as illustrated in Figure 1. Integrally formed 90 on the spring controlled bracket arm 129 is an upwardly directed bracket arm 131 having a ball handle 132 formed on the upper end thereof. Pivots supported on the upper horizontal portion of the bracket arm 131 is a fulcrumed trigger or lever 133 one 95 end of which projects over the ball handle 132 while the other end has connected therewith the upper end of a latch rod 134. The lower end of the latch rod 134 projects 100 through the opening in the bracket arm 129 105 and into an opening provided in the horizontal flange of an angle bar 135 which is secured to the machine frame. A coiled spring 136 is engaged around the latch rod 134 with the lower end of said spring resting against a 110 collar 137 secured on said latch rod. The spring 136 is provided for the purpose of holding the lower end of the latch rod 134 115 projected through the apertures in the bracket arm 129 with the lower end of said latch rod 120 engaged in the aperture provided in the angle bar 135 to hold the bracket arm 129 against rotation by the action of the spring 130 thereby preventing rotation of the clutch control shaft 127.

The machine is also provided with a dish stacking mechanism operable from the machine and comprising a plunger 138 the upper end of which is curved downwardly and has a conical pusher head 139 mounted on the 125 end thereof and adapted to be moved into a position to engage in a discharged receptacle or dish to move the same into the stacking mechanism as hereinafter described. The plunger rod 138 is slidably mounted and pro- 130

jects through a guide sleeve 140 integrally formed on the upper end of a standard or bracket 141 the lower end of which is securely supported on the horizontal flange of the angle bar 135. Secured to the lower projecting end of the plunger rod 138 below the guide sleeve 140 is a coupler 142 to which the upper end of a plunger link or bar 143 is pivotally connected. The lower end of the link 143 is pivotally connected to the end of the long arm of a bell crank 144. The bell crank 144 is pivotally supported on a shaft 145 (Figure 3) supported in suitable bearings mounted on the machine frame. Pivotally connected to the end of the short arm of the bell crank 144 is the upper end of a connecting rod 146. The lower end of the connecting rod 146 is pivotally connected to the free end of a crank arm 147 the other end of which is secured to one projecting end of the shaft 108. Also secured on the shaft 108 between the bearing 110 and the hub of the bell crank 106—107 is a crank arm 148 on the free end of which a roller 149 is mounted. The roller 149 is positioned to track on the periphery of the cam 119 to be actuated thereby. For the purpose of holding the roller 149 in resilient contact with the flange 119 a coiled spring 178 is provided with the lower end of said spring 178 connected to the short arm of the bell crank 144 while the upper end of said coiled spring is connected to a cross member of the machine frame. For the purpose of holding the roller 112 in contact with the periphery of the cam 113 a coiled controlled spring 150 is provided with the lower end of said control spring connected to the long bell crank arm 106 (Figure 3). The upper end of the coiled spring 150 is attached to a cross member of the machine frame.

The pusher head 139 is adapted to be actuated by the control cam 119 so that, when a dish 151 (Figure 3) is removed from the forming mechanism and transferred over the table 32 by the transfer bracket 99, said pusher head will move into engagement with the dish 151 to push the dish downwardly through an opening 152 provided in a plate 153 which is mounted to set in the cut out portion in the table 32. Secured to the bottom of the plate 153 by means of screws or other suitable means is a pair of oppositely positioned segment shaped retaining rails or guide segments 154. The inner curved edges of the guide segments 154 project into a peripheral groove 155 provided in the outer periphery of a dish receiving sleeve or collar 156. The dish receiving sleeve 156 is positioned below the plate 153. Secured on the inner face of the sleeve 156 between suitable guide ribs is a plurality of plates the upper ends of which are tapered and bent inwardly and downwardly to afford inclined spring tongues or fingers 157 which act to prevent dishes from moving upwardly out of said

sleeve 156 and through the opening 152 in the table plate 153. Integrally formed on the outer periphery of the sleeve 156 is a ring gear 158.

Removably projecting into the lower end of the ring gear sleeve 156 is the upper end of a receptacle or dish receiving tube or can 159 having a longitudinal slot or opening 160 therein. The tube 159 is adapted to receive the dishes in nested relation one within the other due to the operation of the pusher head 139. Formed on the inner face of the bottom 161 of the can 159 is a plurality of vanes or plates 162 which serve to afford a pocket for receiving a tapered or conical dish receiving holder 163. The bottom of the holder 163 is provided with a boss or base 164 having a recess or notch 165 in the bottom thereof (Figure 10). The can 159 has the bottom thereof removably seated in a can holding disk or plate 166 provided with a passaged boss 167 which is supported upon the horizontal flange of the angle bracket 135. Projecting through an opening in the angle bracket 135 and through the boss 167 is the upper end of a slideable stem or rod 168. The upper end of the stem 168 also slidably projects through the apertured bottom 161 of the dish receiving can and seats in the recess 165 of the dish holder 163. The stem 168 is long enough to permit the holder 163 to be raised to the top of the can 159. Secured on the lower end of the stem 168 is a head 169 to which a radially directed arm 170 is secured. Connected to the outer end of the arm 170 is one end of a rope or cable 171 to the other end of which a counterweight 172 is secured. The cable 171 passes over guide pulleys 173 which are supported on the angle bar 135.

For the purpose of rotating the can or tube 159 at predetermined times to cause the deposited dishes to be nested within the tube with the folded portions thereof staggered, a pinion 174 is positioned to mesh with the ring gear 158 (Figure 9). The pinion 174 is secured on the upper end of a vertical shaft 175 which is positioned adjacent the can or tube 159 with the lower end of said shaft projecting through a bearing plate 176 mounted upon the bearing plate 111. Secured on the lower projecting end of the vertical shaft 175 is a bevel pinion 177 which is in mesh with the bevel pinion 118.

The operation is as follows:

To operate the receptacle forming machine 120 a driving belt connected with any suitable source of power is trained over the driving pulley 3 to cause rotation of the main drive shaft 2. A drive from the shaft 2 is transmitted through the chain 17 to the auxiliary shaft 18 and to the bevel pinion 20. The bevel pinion 20 is thus adapted to impart a drive to the blank feeding mechanism of the machine. The bevel pinion 20 being in mesh with the bevel gear 21 acts to rotate the same 130

and the gear 46. The hollow shaft 22 is thus rotated.

When the machine is started a stack of circular sundae dish blanks is deposited in the magazine 33 with the lowermost blank resting upon the pin 35 and upon the disks 29 of the feed reel.

When it is desired to cause dish blanks to be fed out of the magazine 33 onto the table 32 an operator pushes inwardly on the knob or handle 25 thereby causing the shaft 24 to slide inwardly with the pins 26 moving in the slots 27 of the hollow shaft 22 into a position to coat with the pin 28 secured in one end of the feed reel. The pins 26 thus act to transmit a drive from the hollow shaft 22 to the blank feed reel through the pin 28. The reel 29—30 is thus rotated and when the friction pad 31 on said reel moves into its uppermost position it frictionally engages the lowermost blank in the magazine 33 and feeds said blank from the magazine between the rollers 36 and 37. The roller 36 receives a drive from the gears 46 and 45 while the lower roller 37 is rotated from the upper roller through the small gears 41 and 42. The rotating feed rollers 36 and 37 act to feed the blank from the magazine onto the table 32. As the above operation takes place the pusher arms 53 are in their retracted position engaged in the grooves of the lower feed roller 37. After the dish blank has been sufficiently advanced by the rollers 36 and 37 the pusher arms 53 are actuated by means of the cam 47 (Figure 7) which coacts with the roller 48 on the arm 49 to cause said arm to slide away from the hollow shaft 22. The crank arm 50 is thus actuated to rotate the shaft 51 to cause the pusher arms 53 to swing upwardly through the table slots 54 to engage and push the advanced dish blank forwardly on the table 32 against the stops 55. As the pusher arms 53 push the blank against the stops 55 the upper ends of the positioning arms 74 are actuated in the table slot 75 and move inwardly toward the front of the machine to further position and center the dish blank on the table in the field of operation of the dish forming mechanism. The positioning arms 74 are carried by the arm 76 which is secured on the shaft 77. The shaft 77 is rocked or partially rotated by means of the bell crank 79 the roller 83 of which coacts with the cam 84 mounted on the cam shaft 2.

55 The gripper plates 191 of the dish forming mechanisms are separated during the time the blank is being positioned; this separation is accomplished by swinging the member 65 about its pivoted point 69 by means of the cam 88 which acts on the roller 87 to raise the bar 89. Elevation of the bar 89 causes one end of the fulcrumed arm 90 to move upwardly thereby contacting the shoe 91. The shoe 91 being mounted on one of the arms 66 thus causes elevation of the forming member 65

and compression of the spring 73 and at the same time separates the gripper plates 191. At a predetermined time in the operation of the cam 88 the roller 87 is permitted to drop so that the forming member 65 is permitted to be gradually lowered so that the gripping plates 191 are closed by the action of control springs to permit said gripping plates to grip the centered dish blank. At the time a dish blank is advanced onto the table 32 against the stops 55 the cam 61 on the shaft 2 is adapted to actuate the fulcrumed bar 57 thereby causing the rod or pin 56 to be projected upwardly through the opening in the table to elevate a portion of the advanced disk blank so that said blank engaged between the gripping plates of the dish forming mechanism may be moved away from the stop pins 55 and be positioned at an angle to more easily pass over an edge of the table when the gripping plates are rotated to form the blank into a sundae dish.

90 The action of the disk 7 and its roller 8 upon the Geneva gear 9 now commences and the gripping plates 191 are thus rotated through a half revolution to fold the gripped blank into the form of a conical sundae dish. After the forming of the dish as described a raised portion on the cam 88 comes into engagement with the roller 87 to raise the forming member 65 to cause separation of the gripping plates. The advanced blank having been formed into a receptacle or dish by the forming mechanism it is now ready to be discharged from the forming mechanisms and delivered to the stacking attachment of the machine.

95 At the beginning of the operation of the machine an operator merely swings the control arm 131 into the position illustrated in Figure 1 thereby causing the arm 129 to tension the spring 130 while the latch rod 134 is moved into a position to engage in the notch in the horizontal flange of the angle bar 135. Swinging of the arm 129 causes a 100 partial rotation of the vertical shaft 127 thereby causing the yoke 124 to move the clutch collar 122 into the position illustrated in Figure 4 wherein the pin 120 is adapted to engage in the notch 121 of the shiftable clutch collar 122. When the clutch is thrown in as described a drive is imparted to the cam 113 and thereby to the crank 106—107 which 105 in turn operates the connecting rod 105 and the bell crank 101—104 to cause the receptacle pusher bracket 99 to move outwardly across the table 32 to transfer the formed receptacle or dish from the forming mechanisms into a 110 position over the opening 152 in the table plate 153. The dish is thus positioned above the receiving tube or can 159. The cam 111 on the shaft 114 coacts with the roller 149 to operate the crank arm 148 and thereby the crank arm 147 to cause operation of the connecting rod 146. The connecting rod 146 115

actuates the bell crank 144 on the shaft 145 to cause reciprocation of the link bar 143 and the pusher rod 138 of the receptacle stacking mechanism. With the lowering of the pusher rod 138 the plunger head 139 is lowered to seat in the formed dish and push said dish from the transfer bracket 99 through the opening 152 in the table plate 153. The dish is thus pushed into the rotatable sleeve 156 past the resilient fingers 157 and into the upper end of the receptacle receiving tube or can 159. As the dish is pushed through the sleeve 156 the edge of the dish is slightly indented while passing the resilient fingers 157. When said fingers have passed the fingers 157, the dish automatically opens up again so that the rim of the dish will engage beneath the retaining fingers 157 to prevent the dish from moving or spring upwardly out through the table plate aperture 152. When a dish is pushed into the tube 159 the dish holder 163 is held in its uppermost position in the can by the counterweight 172 which acts to hold the stem or shaft 168 in a raised position thereby also causing elevation of the dish holder 163 within the tube 159. The dishes when formed are thus stacked in nested relation one within the other in the receiving tube 159 supported by the dish holder 163. When the clutch sleeve 122 is in driving position the bevel gear 118 is also rotated thereby causing rotation of the bevel gear 177 on the vertical shaft 175. The pinion 174 on the upper end of the shaft 175 is thus also rotated and acts to transmit a drive to the ring gear 158. Rotation of the ring gear 158 causes rotation of the sleeve 156 and the tube 159 each time a formed dish is delivered into said tube. By rotating the receptacle or dish receiving tube 159 when dishes are delivered thereto the dishes are stacked nested one within the other so that the folded portions of the dishes are deposited in staggered relation to permit the dishes to form a straight stack which will not tend to bend or curve as is the case when dishes are stacked with the folded portions of said dishes deposited one above the other. The dishes are thus transferred from the forming mechanisms and delivered into the receiving tube 159 and are prevented from springing upwardly out of the table opening 152 by the retaining fingers 157. Each time a dish is deposited in the tube 159 the dish holder 163 is lowered a predetermined amount so that the stack of dishes may be increased in height with the counter weight 172 acting to hold the dish holder 163 resiliently against the lowermost dish thereby serving to apply a continuous pressure against all of the dishes in the stack. When the dish holder 163 reaches the bottom of the tube 159 the operator in charge of the machine manually pulls the knob 25 outwardly thereby causing the driving pin 26 on the shaft 24 to be moved

out of engagement with the reel pin 28. The blank feed mechanism may thus be stopped at any desired time either when the tube is completely filled or only partially filled.

The dish transfer mechanisms controlled by the operation of the cam 113 and the dish stacking mechanisms controlled by the operation of the cam 119 may be stopped at any desired time by the operator who merely presses downwardly on the control lever 133 (Figure 3) thereby lifting the latch rod 134 against the action of the spring 136. When the latch rod 134 is lifted the lower end of the rod is lifted out of engagement with the horizontal flange of the angle bar 135. The clutch control arm 129 is thus unlatched or released permitting the control spring 130 to swing the arm 129 away from the tube 159 thereby causing the clutch control shaft 127 to rotate to cause the yoke 124 to move the clutch sleeve 122 into a released position out of engagement with the pin 120. The drives to the cams 113 and 119 and the bevel gear 118 are thus discontinued thereby stopping the dish transfer mechanism and the dish stacking mechanism.

The shaft 13 is driven from the gears 11 and 12 the operation of which are governed by the Geneva gear 9 which is adapted to receive a drive from the roller 8 carried by the disk 7 mounted on the main driving shaft 2. The bevel pinion 14 being mounted on the shaft 13 acts to operate the bevel pinion 15 thereby causing operation of the dish forming mechanisms. If, however, at any time, it is desired to stop the operation of the dish forming mechanisms the hand wheel 64 may be operated to cause the clutch 63 to be moved into a position wherein the drive from the shaft 13 is not transmitted to the dish forming mechanisms.

It will thus be noted that a dish or receptacle forming unit is adapted to receive a drive from a common source and furthermore is adapted to have the blank feeding mechanisms, and the dish forming mechanisms to be controlled independently of the dish transfer mechanisms and the dish stacking mechanisms to permit starting or stopping of said various mechanisms of a unit at the will of an operator, without interfering with the operation of similar mechanisms of other dish or receptacle forming units which may be connected with the same driving source.

A receptacle forming machine has thus been provided wherein any desired number of units may be connected to receive a drive from a common source with each of said units having the various mechanisms thereof adapted to be independently controlled without interfering with the operation of any of the other machine units.

I am aware that many changes may be made and numerous details of construction may be varied through a wide range without

departing from the principles of this invention, and I therefore do not purpose limiting the patent granted hereon, otherwise than necessitated by the prior art.

5 6. I claim as my invention:

1. A dish forming machine comprising automatic dish forming mechanisms, a mechanism for automatically feeding dish blanks into the field of operation of said forming mechanisms to be formed into dishes, means for automatically centering the dish blanks, means operated from the machine for automatically elevating the centered dish blanks to facilitate forming of said blanks into dishes, means for automatically transferring the formed dishes from the forming mechanisms over said stacking mechanism, and means for automatically pushing the dishes into said stacking mechanism.
- 10 2. In a dish forming machine the combination with a dish forming mechanism, of a blank feed mechanism for advancing blanks into the field of operation of said dish forming mechanism, mechanisms for automatically centering the advanced dish blanks, and means for elevating portions of said dish blanks to permit the same to be more readily operated upon by said dish forming mechanism.
- 15 3. In a dish forming machine the combination with dish forming mechanisms, of a blank feeding mechanism adapted to feed blanks into the field of operation of said dish forming mechanisms, means for automatically centering the dish blanks, a slideable pin for elevating the advanced centered dish blanks to permit the same to be more readily formed into dishes by the forming mechanisms, and cam operated means for actuating said pin.
- 20 4. A dish forming machine comprising a driving mechanism, a dish forming mechanism connected to be driven thereby, a blank feed mechanism, means for independently connecting the same to said driving mechanism to receive a drive therefrom to advance dish blanks into the field of operation of said dish forming mechanism, means for disconnecting the dish forming mechanism from said driving means independently of said blank feeding mechanism, and means for disconnecting the blank feeding mechanism from said driving means independently of said dish forming mechanism.
- 25 5. A dish forming machine comprising a driving mechanism, a dish forming mechanism connected to be driven thereby, means for independently disconnecting said dish forming mechanism from said driving mechanism, a blank feeding mechanism connected to receive a drive from said driving mechanism, means for independently disconnecting the blank feeding mechanism from said driving mechanism, means for automatically centering blanks in the field of operation of said

dish forming mechanism when said blanks are advanced by said blank feeding mechanism, a slideable pin for raising the centered dish blanks to permit the same to be more readily formed into dishes by the dish forming mechanism, a fulcrumed member supporting said pin, and a cam operated by said driving mechanism for actuating said fulcrumed member to cause operation of said pin.

70 75 6. The combination with a dish forming machine, of a table, a blank feed mechanism operable from the machine for advancing dish blanks over said table, means operated from the machine for automatically centering the advanced dish blanks on said table, and means adapted to project through the table to raise the centered blanks.

80 85 90 7. In a dish forming machine, the combination with a table, of a dish forming mechanism operable from the machine, means for moving a dish blank over said table into the field of operation of said dish forming mechanism, and means operated through said table to raise the advanced centered dish blank off of the table to permit the dish forming mechanism to more easily draw said blank over an edge of said table as the blank is formed into a dish.

95 100 105 8. In an automatic dish forming machine the combination with a driving means, of a dish forming mechanism connected to receive a drive therefrom, means operated from the driving mechanism to advance a dish blank toward said dish forming mechanism, and a cam actuated pin operable from said driving mechanism adapted to raise the dish blank into a position to permit the same to be more easily formed into a dish by the dish forming mechanism.

110 115 120 9. In a dish forming machine the combination with a driving mechanism, of a dish forming mechanism connected to receive a drive therefrom, a cam operated by said driving mechanism, and a device operable by said cam for elevating a dish blank into a position to permit the same to be more easily formed into a dish by the dish forming mechanism.

125 130 135 10. In a dish forming machine the combination with a driving means, of a dish forming mechanism adapted to engage blanks and form the same into dishes, a dish stacking mechanism, a dish transfer mechanism for moving formed dishes from said dish forming mechanism into the field of operation of said dish stacking mechanism, cam mechanisms for operating said dish stacking mechanism and said dish transfer mechanism, a clutch mechanism, and means for actuating said clutch to cause said cam mechanisms to be connected with or disconnected from said driving means.

140 11. A dish forming machine comprising a driving mechanism, a table, a dish forming

mechanism connected to be driven by said driving mechanism, a blank feeding mechanism connected to be operated by said driving mechanism, a blank stacking mechanism

- 5 connected to receive a drive from said driving mechanism, a dish transfer mechanism adapted to be connected with said driving mechanism to transfer formed dishes from said dish forming mechanism to said dish
- 10 stacking mechanism, means for independently disconnecting said dish forming mechanism from said driving mechanism, a device for independently disconnecting said blank feeding mechanism from said driving mech-
- 15 anism, and means for simultaneously disconnecting said dish stacking mechanism and said dish transfer mechanism from said driving mechanism.

12. A dish forming machine of the class

- 20 described comprising a driving mechanism, a dish forming mechanism, a blank feeding mechanism, a dish stacking mechanism, a dish transfer mechanism, and a plurality of manually operable control devices for simultaneously disconnecting the dish stacking mechanism and the dish transfer mechanism from said driving mechanism independently of the disconnection of said dish forming mechanism and said blank feeding mecha-
- 25 nism.

13. A receptacle forming machine comprising a driving mechanism, a plurality of receptacle forming units, and a plurality of independently controlled devices for each of said units to permit the devices of each of said units to be selectively connected with or disconnected from said driving mechanism independently of the operation of the remaining units.

- 40 14. A dish forming machine of the class described comprising a driving mechanism, a plurality of dish forming units each comprising a dish forming mechanism, a blank feeding mechanism, a dish transfer mechanism, and a dish stacking mechanism, and a plurality of independently controlled devices for each of said units to permit the various mechanisms of each unit to be selectively connected with or disconnected from said driving mechanism independently of the other units.
- 45
- 50

15. In a dish forming machine the combination with a driving mechanism, of a dish transfer mechanism, a dish stacking mechanism, cam operated means for actuating said transfer mechanism and said dish stacking mechanism, a clutch device, and means for actuating said clutch device to permit the cam mechanisms to be connected with said driving mechanism.

- 55 16. In a dish forming machine the combination with a driving mechanism, of a dish transfer mechanism, a dish stacking mechanism, a plurality of devices for independently operating said dish transfer mechanism and
- 60
- 65

said dish stacking mechanism, cams for operating said devices, a clutch device for permitting a drive to be transferred from said driving mechanism to said cams, and means for operating said clutch mechanism to cause 70 said drive from said driving mechanism to said cams to be discontinued.

17. A dish forming machine of the class described comprising a frame, a common driving mechanism thereon, a plurality of 75 dish forming units each comprising feeding, forming, transfer and stacking mechanisms, and a plurality of independently operable control means for each of said units adapted to be operated to permit said mechanisms of each unit to be connected with or disconnected from said common driving mechanism independent of the other units which might be connected with said driving mechanism.

18. A multiple unit receptacle forming 80 machine comprising a frame, a common driving means supported thereon, a plurality of units, and a plurality of control mechanisms adapted to receive a drive from said common driving means and further adapted to be independently operated to permit a selective operation of the various mechanisms forming each unit as well as independent operation of the various units with respect to one another.

19. A receptacle forming machine comprising a driving mechanism, a forming mechanism, a blank feeding mechanism, an independent control for said forming mechanism for independently connecting and disconnecting said forming mechanism to and from said driving mechanism, an independent control for said feeding mechanism for independently connecting the same with and disconnecting the same from said driving mechanism, a receptacle transfer mechanism 100 and a receptacle stacking mechanism and a common control mechanism for said transfer and stacking mechanisms adapted to permit the same to be connected with or disconnected from said driving mechanism independently of the forming mechanism and said feeding mechanism.

20. A receptacle forming machine comprising a driving mechanism, a forming mechanism, a feeding mechanism, a transfer 115 mechanism and a stacking mechanism, all connected to receive a drive from said driving mechanism, and a plurality of manually operable devices whereby the various mechanisms may be selectively disconnected from 120 said driving mechanism.

21. In a receptacle forming machine the combination with a dish forming mechanism, of a dish receiving device, reciprocating means for delivering a receptacle from said forming mechanism to said receiving device, a bell crank connected with said reciprocating means, a rod connected to said bell crank, a second bell crank connected with said rod, a roller on said second bell crank, a cam for 125 130

coaction with said roller, a clutch for coaction with said cam, a driving means, and manually controlled means for operating said clutch to cause a drive from said driving means to be imparted to said cam.

22. In a dish forming machine the combination with a dish forming mechanism, a dish receiving device, means for transferring a dish from said forming mechanism over 10 said receiving device, reciprocating means for delivering the dish into said receiving device, a fulcrumed member connected with said reciprocating means, a rod connected with said fulcrumed member, pivoted means connected with said rod, a roller on said pivoted means, a cam coacting with said roller, a clutch, a driving means, and manually con-

trolled means for connecting the clutch with said cam to cause a drive from said driving means to be imparted to the cam.

23. In a receptacle forming machine the combination with an apertured table, of a driving device, a pin coacting with said apertured table to project therethrough to raise blanks on said table, a fulcrumed member connected with said pin, a roller on said fulcrumed member, and a cam on said driving device adapted to coact with said roller to cause operation of said pin at predetermined times.

In testimony whereof I have hereunto subscribed my name.

CESARE BARBIERI.
